DESIGN FOR A COMBINED BUREAU, BED, AND BOOKCASE

Herman L. Mash and Harold P. Gould,
Philadelphia, Pa.

Application September 11, 1939, Serial No. 87,132

Term of patent 3½ years

To all whom it may concern:

Be it known that we, Herman L. Mash and Harold P. Gould, citizens of the United States, residing at Philadelphia, in the county of Philadelphia and State of Pennsylvania, have invented a certain new, original, and ornamental Design for a Combined Bureau, Bed, and Bookcase, of which the following is a specification, reference being had to the accompanying drawing forming part thereof.

In the drawing:

Fig. 1 is a front perspective view of a combined bureau, bed, and bookcase showing our design; and

Fig. 2 is a front perspective view of the bureau and bookcase portion of the device, the bed being removed for better disclosure of the bureau and bookcase.

The rear and opposite side of our device are substantially plane.

We claim:

The ornamental design for a combined bureau, bed, and bookcase, as shown and described.

HERMAN L. MASH.
HAROLD P. GOULD.
